Inventor:
Abraham S. Levey
by S. W. Bates, Atty.

UNITED STATES PATENT OFFICE.

ABRAHAM S. LEVEY, OF PORTLAND, MAINE.

AUTOMOBILE SIGNAL.

Application filed March 18, 1921. Serial No. 452,642.

To all whom it may concern:

Be it known that I, ABRAHAM S. LEVEY, a citizen of the United States, residing at Portland, in the county of Cumberland and State of Maine, have invented certain new and useful Improvements in Automobile Signals, of which the following is a specification.

My invention relates to a signal device for 10 automobiles to be attached to the rear of the machine for indicating the movements of the machine, the design being such that it may also be attached to the front portion of the machine where the mirror is now 15 located.

My invention contemplates the use of electric lights placed in different circuits and displayed in such a way that the form in which the lights are arranged will indicate 20 what the movements of the machine will be, that is to say, whether it will stop, turn to the right or to the left.

According to my invention, I make use of a casing which is preferably oblong in shape 25 and comparatively flat and provided with a glass face.

I have illustrated my invention by means of the accompanying drawing in which:

Fig. 1 shows a face view of my signal 30 and;

Fig. 2 shows a section on the line, 1, i.

Referring to the drawing:

2 shows the body of the casing which is preferably oblong in shape and disposed in 35 a horizontal position, 3 is a diaphragm or intermediate bottom and 4 is the foundation plate leaving between it and the base diaphragm 3 a chamber 5 in which the various wires are disposed.

40 The front of the signal is made up of a transparent face 6 which may be of glass or other transparent material and between the diaphragm 3 and the face 6 the figures or characters are disposed.

45 The arrow 7 extends nearly the length of the signal and is preferably made of a thin metal strip formed into a channel, the edges of which rest against the glass face 6. The base of the channel is soldered or otherwise 50 attached to the diaphragm 3 which is also of metal.

At each end of the arrow 7 is a pointed head 8 indicating direction in the usual manner.

55 The lower part 9 of the letter "L" is se-

cured immediately below the arrow and its upper portion 10 is formed immediately above the arrow so that the effect is that the arrow extends through the letter and divides it into two parts.

60 The letters L, S and R are formed of thin metal, U-shaped in cross section and are held firmly in place by being attached to the diaphragm 3 and the edges of each letter resting against the transparent face 6. 65 Referring to the letter L; for the purpose of illuminating the inside of the letter a small electric light 11 extends up through the bottom of the channel 9 and the diaphragm 3 with a connecting wire 12 which extends 70 into the space 5 and is led with other lights hereinafter spoken of through a suitable cable, to the body of the automobile.

75 The central letter S and the letter R are formed in the same manner as the letter L and the arrow, the upper half of each letter being above the arrow and the lower half below the arrow.

80 Each enclosed space is provided with one or more electric lights for illuminating the enclosure according to the shape of the letter. Two partitions 13 and 14 extend across the shaft of the arrow so as to shut off a portion of each end and to leave a portion of the center when desired, lights are placed 85 in the arrow to illuminate either the ends or the straight center as may be required.

85 Electric circuits are so arranged that all the lights may be shut off except the letter L and the left hand of the arrow or the letter R and the right hand of the arrow or the letter S in the central portion of the arrow.

90 These three signals will indicate that the automobile will either turn to the left or to the right or that it will stop or slow down so that any following car may be governed accordingly.

95 A signal such as I have described may be cheaply manufactured, it is exceedingly simple to understand the signals and will when used often avoid accidents where the traffic is great.

100 While the signal is principally designed for the rear of the car it may also be used on a much smaller scale in front of the car, for instance, on the back of the mirror.

I claim:

105 A signal for automobiles including a casing with a flat glass face, an elongated arrow 110

with a head at each end and letters indicating movements of the automobile crossing said arrow, the arrow and letters being of thin material formed of open channels with ⁵ U-shaped cross section, the edges of the open channel resting adjacent to the glass face, the section of arrow opposite each letter be-

ing separated from the adjacent section of the arrow by an intervening diaphragm and the three groups of electric lights within the ¹⁰ letters and adjacent arrow sections to illuminate the interior of the three sections to form three separate groups.

ABRAHAM S. LEVEY.
